UNITED STATES PATENT OFFICE.

JOHN FOUNTAIN, JR., OF ELIZABETH, NEW JERSEY.

OUTLET-BOX.

SPECIFICATION forming part of Letters Patent No. 664,939, dated January 1, 1901.

Application filed October 27, 1900. Serial No. 34,549. (No model.)

To all whom it may concern:

Be it known that I, JOHN FOUNTAIN, Jr., a citizen of the United States, residing at Elizabeth, in the county of Union and State of New Jersey, have invented certain new and useful Improvements in Outlet-Boxes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to improvements in outlet-boxes designed for making connections in the electrical wiring of buildings; and my present invention has for its primary object to provide a simple and novel construction 20 of outlet-box which is to be used as a fixture-support in the side walls, partitions, and ceilings, the box being of such construction that the workman can easily and quickly provide the box either in its bottom or the sides with 25 various openings for the reception and the direct attachment thereto of the gas or electric fixtures employed in the construction of buildings.

The principal objects of my invention are to 30 provide a novel construction of outlet-box with a means of direct attachment to it of gas or electric fixtures and also to so construct the box that openings can be readily made in the same at various points as desired, there- 35 by enabling the workman to make any com- bination required in placing the electric con- duct in the walls or other parts of a building, and also to so construct the box that it can be readily adapted for use with combination- 40 fixtures.

A further object of this invention is to pro- 45 vide a box with one or more openings at the time of placing it in position, as may be de- sired, the box being convenient in use and easily secured in fixed position and avoiding all danger of accidental leaks or electrical grounds.

50 My invention therefore consists in the novel construction of outlet-box hereinafter fully described, in which the bottom or sides of the box, or both, are provided with a series of openings over which are cast and secured in

place suitable plates or disks which can be readily broken away at the point desired to provide the box with one or more openings, 55 as desired, such opening or openings having nearly perfect edges to obviate the necessity of filing away objectionable burs or rough edges.

The invention consists, furthermore, in the 60 various novel features and arrangements of the several parts, all of which will be fully described in the accompanying specification and then finally embodied in the clauses of the claim which form a part of this specifica- 65 tion.

The invention is clearly illustrated in the accompanying drawings, in which—

Figure 1 is a top or plan view of an outlet- 70 box made according to my present invention; and Fig. 2 is a side view of the same, the form of box illustrated being composed of an upper and lower section. Fig. 3 is a plan view of the lower section of the box, illustrating the general arrangement of the closing plates 75 or disks secured in place over the openings in the bottom and sides of said box-section. Fig. 4 is a vertical section of the lower box-section, taken on line 4-4 in said Fig. 3, and a vertical section of the upper box-section, said sec- 80 tion being taken centrally across said upper box-section. Fig. 6 is a plan or top view of the lower box-section represented in said Fig. 3, showing the same with two of the closing disks or plates broken out to provide the openings 85 represented in said figure; and Fig. 5 is a sec- tional view of the lower and upper box-sec- 90 tions, similar to the section represented in Fig. 4, but said view illustrating one of the closing disks or plates broken out to provide an open- 95 ing in the side of the outlet-box. Fig. 7 is a plan view of one of the closing-disks. Fig. 8 is a cross-section of an outlet-box of a slightly- modified construction in which the upper box- 100 section has the closing disks or plates detach- ably secured in position against the upper box-section instead of the lower box-section, as illustrated in Figs. 4 and 5. Fig. 9 is a vertical section of still another form of outlet- box in which the box is cast in one piece, said view representing one manner of arranging the closing disks or plates in depressions in the sand core, so as to cast them in their closing positions against the bottom and sides.

of the box during the casting operation. Figs. 10 and 11 are a plan view and a bottom view, respectively, of a pair of patterns employed in the process of casting the lower and upper box-sections of the outlet-box illustrated in said Figs. 1 to 6, inclusive; and Fig. 12 is a sectional view of these two patterns on an enlarged scale, the sectional representation of the lower half of said figure being taken on line 12-12 in Fig. 10 and the sectional representation of the upper half of said Fig. 12 being taken centrally across the representation of the pattern illustrated in Fig. 11.

Similar letters of reference are employed in all of the said above-described views to indicate corresponding parts.

In Figs. 1 to 6, inclusive, A indicates the complete outlet-box, which comprises a lower box-section A' and an upper box-section A², the two sections being capable of being placed one upon the other in the manner illustrated in Figs. 2, 4, and 5 and being secured together by means of screws b or in any other suitable manner. The said lower box-section A' consists, essentially, of a bottom or base a and the sides a'. The said bottom is provided with suitably-placed screw-holes a² for securing the box-section in position in the wall, ceiling, or other part of a building, and a³ indicates suitably-placed lugs or projections cast in said bottom and provided with holes for securing an electrical or other fixture in position in the section. As will be noticed from the several figures of the drawings, the said bottom or base a is provided with circular openings a⁴, and formed integral with the inner surface of said bottom or base, contiguous to the edge of the said openings a⁴, are suitable projections a⁵. Each projection a⁵ is provided with a holding portion which extends over the marginal edge or circumference of a suitable disk or plate c. In this manner each hole or opening a⁴ is closed by means of a disk or plate c, the same being held in place by the holding portions a⁵, and said disk or plate practically forming an integral part of the said bottom or base by being placed in the pattern previous to the casting operation and being secured in position in the manner to be hereinafter fully set forth. Each side a' of the lower box-section A' is provided with suitably-disposed semicircular openings a⁶, the said upper box-section A² being provided with correspondingly-placed semicircular openings a⁷, which when the two box-sections A' and A² are placed upon each other and are secured together by means of the screws b register with one another, and thereby produce the complete circular openings or holes represented in the figures of the drawings. As illustrated in Figs. 3, 4, 5, and 6, the said lower box-section A' is provided on its inner surface and contiguous with the said semicircular openings a⁶ with upwardly-extending ribs a⁸, which are provided with the grooved parts a⁹ and form guides or holding portions for

embracing edges of certain metallic disks or plates c', substantially as illustrated. In this manner these disks or plates c' close the said openings or holes formed by the semicircular openings a⁶ and a⁷ in the respective box-sections, each disk or plate being held in place by the projecting portions of the grooved ribs a⁸ and also by means of an upwardly-projecting post or stud a¹⁰, formed integral with the base a. The said posts a¹⁰, however, are not absolutely necessary and may be dispensed with, if desired. The said disks or plates c' thus practically form an integral part of the inner surfaces of the sides a' of the lower and upper box-sections A' and A² by being placed in the pattern previous to the casting operation and then being secured in position in the manner to be presently described. It will be clearly evident that the sides of the outlet-box, as well as its bottom or base, may be provided with any desirable number of such openings a⁶ closed by the disks or plates c' and the openings a⁴ closed by the disks or plates c. The upper box-section A² is provided with the usual flanged opening a¹¹, of sufficient diameter to allow the electric wires to be conveniently drawn out through the said upper box-section or cover A². The electric conduits employed to cover the electric wires in buildings are to be passed through any one or more of the openings in the sides or bottom of the outlet-box A. From an inspection of Figs. 5 and 6 it will be seen that any one of the disks or plates c or c' can be readily removed by the workman at the desired point or points where the conduit or conduits containing the electric wires are to be inserted and admitted into the box A by striking the disk or plate on its outer surface a blow with a hammer or other tool, and thereby breaking away the holding-lugs or the parts a⁵ on the base a when a disk or plate c is to be removed or by breaking away portions of the ribs a⁸ and the lugs or studs a¹⁰ when a disk or plate c' is to be removed. Thus it will be obvious that any one or more of the disks or plates c and c' can be broken or forced out from its closing position over the opening in the base or side of the outlet-box for the proper admission of the electric conduit or conduits into the box.

Having now described the general construction of the form of outlet-box represented in said Figs. 1 to 6, inclusive, I will now describe the manner of using the patterns illustrated in Figs. 10 to 12, inclusive, in connection with the disks or plates c and c' for casting the box-sections and for uniting during the casting operation the said disks or plates c and c' to the cast-iron base and sides of the lower box-section A'. The pattern employed in the casting of the said lower box-section A' is represented more especially in Fig. 10, and consists, essentially, of a bottom or base d and the sides d'. The said bottom is formed with the raised portions d² and the depressions or recesses d³ directly beneath said raised portions and also

with the raised projections or lugs d^4 and d^5 , all of which produce in the cast made from said pattern the several parts a^4 , a^5 , and a^{10} in and upon the base or bottom a , which is 5 cast in the impression in the sand made by said pattern after it is withdrawn from the mold. The said pattern d is also provided with the semicircular openings d^6 and grooved ribs d^7 , all of which produce the corresponding parts a^6 and a^8 in the lower box-section 10 A' during the process of casting. The pattern employed in the process of casting the upper box-section A^2 is indicated by the reference-letter d^8 , and it is provided with the 15 semicircular openings d^9 in its sides and the flanged opening d^{10} for producing the corresponding parts in the said upper box-section A^2 , as will be clearly understood. The manner of arranging the several metallic disks 20 or plates in the mold formed by the said patterns is clear from an inspection of said Fig. 12, and when the molten metal is poured into the mold and cools then the several disks or plates c and c' will be held in their respective 25 positions above the respective openings in the base and sides of the box-section, with the several portions a^5 , a^9 , and a^{10} embracing portions of the circumferential edges of the said disks or plates, substantially in the manner 30 illustrated in Figs. 1 to 6 of the drawings and as hereinabove described.

35 In lieu of providing the lower box-section A' with the holding-ribs and the holding-lugs a^{10} the inner surfaces of the sides of the upper box-section A² may be provided with similarly-constructed holding-ribs a^{12} and holding-projections a^{13} for retaining the disks or plates c' in position, as clearly illustrated in Fig. 8 of the drawings.

40 When the outlet-box is made in one piece, as indicated in Fig. 9, then the disks or plates c and c' are laid directly in the core e, as shown in said figure, and when the molten metal is poured into the mold then said disks or plates 45 will be cast directly to the inner surfaces of the outlet-box over the openings formed therein, from which said disks or plates can be broken away when desired in the manner hereinabove described to produce a circular 50 hole or holes in the bottom or sides of the box having a perfect edge which needs no filing away of burs or rough portions.

The herein - described outlet - box can be readily secured in position in the side walls, the ceiling, or in any portion of the building, and any one or more of the closing disks or plates of any configuration can be readily broken away from their closing positions in the box for the admission into the box of the conduit or conduits containing the electric wires at the desired points.

I am aware that changes may be made in the various arrangements and combinations of the parts as well as in the manner of detachably securing the closing disk or disks or plates in position over the opening or openings in the bottom and sides of the box with-

out departing from the scope of my present invention. Hence I do not limit my invention to the exact arrangements and combinations of the parts as described in the accompanying specification and as illustrated in the drawings thereof; nor do I confine myself to the exact details of the construction of the various parts of the box nor to the exact shape and configuration of either the lower or the upper box-sections.

Having thus described my invention, what I claim is—

1. An outlet-box for electric wires or other fixtures, the box having one or more openings, and a separate disk or disks or plates over said opening or openings, cast in position over the opening or openings and forming an integral portion of the box, said disk or disks or plates capable of being broken away to form an opening or openings in the box, substantially as and for the purposes set forth. 85

2. An outlet-box for electric wires or other fixtures, the box having one or more openings, and a separate disk or disks or plates over said opening or openings, cast in position over the opening or openings and forming an integral portion of the box, and lugs or holding portions cast integral with the box having parts thereof cast over the peripheral edges of said disk or disks or plates, said lugs or holding portions and said disk or disks or plates capable of being broken away to form an opening or openings in the box, substantially as and for the purposes set forth. 90 95 100

3. An outlet-box for electric wires or other fixtures, the box having one or more openings in its bottom or base, a separate disk or disks or plates over said opening or openings, cast in position over the opening or openings in said base or bottom, and said box having one or more openings in its sides, and a separate disk or disks or plates over said opening or openings in the sides of the box, cast in position over said opening or openings, said disk or disks or plates in either the bottom or sides of the box capable of being broken away to form an opening or openings, substantially as and for the purposes set forth. 115

4. An outlet-box for electric wires or other fixtures, the box having one or more openings in its bottom or base, a separate disk or disks or plates over said opening or openings, cast in position over the opening or openings in said base or bottom, and lugs or holding portions cast integral with said base or bottom having parts thereof cast over the peripheral edges of said disk or disks or plates on said base or bottom, said lugs or holding portions and said disk or disks or plates capable of being broken away to form an opening or openings in said base or bottom, said box having one or more openings in its sides, and a separate disk or plate over said opening or openings in the side of said box, cast in position over said opening or openings in the side, grooved ribs cast integral with the said sides, having portions of said ribs cast over the peripheral 120 125 130 135

edges of said disk or disks or plates, said ribs and said disk or disks or plates capable of being broken away to form an opening or openings in the side of the box, substantially as and for the purposes set forth.

5. An outlet-box for electric wires or other fixtures, consisting, essentially, of a lower and an upper box-section, and means for securing said box-sections together, semicircular openings in said lower box-section, semicircular openings in said upper box-section, said openings in the upper box-section registering with the openings in the lower box-section, and separate disks or plates cast in position over said openings in the lower box-section, capable of being broken away to form an opening or openings, substantially as and for the purposes set forth.

6. An outlet-box for electric wires or other fixtures, consisting, essentially, of a lower and an upper box-section, and means for securing said box-sections together, semicircular openings in said lower box-section, semicircular openings in said upper box-section, said openings in the upper box-section registering with the openings in the lower box-section, separate disks or plates cast in position over said openings in the lower box-section, and grooved ribs cast integral with one of said box-sections, having portions of said ribs cast over the peripheral edges of said disks or plates, said ribs and said disks or plates capable of being broken away to form an opening or openings, substantially as and for the purposes set forth.

7. An outlet-box for electric wires or other fixtures, comprising a lower and an upper box-section, and means for securing said box-sections together, said lower box-section consisting, essentially, of a base or bottom a , having one or more openings, a separate disk or disks or plates over said opening or openings, cast in position over said opening or openings, and capable of being broken away, and sides a' to

said lower box-section having semicircular 45 openings, the upper box-section having semicircular openings registering with the semicircular openings in the sides of the lower box-section, separate disks or plates cast in position over said openings in the sides of the lower box-section, said disks or plates capable of being broken away to form an opening or openings in the said sides of the lower and upper box-sections, substantially as and for the purposes set forth.

8. An outlet-box for electric wires or other fixtures, comprising a lower and an upper box-section, and means for securing said box-sections together, said lower box-section consisting, essentially, of a base or bottom a , having one or more openings, a separate disk or disks or plates over said opening or openings, cast in position over said opening or openings, and holding lugs or projections a' on said bottom or base having portions of said lugs cast over 65 the edges of said disk or disks or plates, said lugs and said disk or disks or plates capable of being broken away, and sides a' to said lower box-section having semicircular openings, the upper box-section being provided with semicircular openings registering with the semicircular openings in the sides of said lower box-section, separate disks or plates cast in position over said openings in the sides of the lower box-section, and grooved ribs cast 70 integral with one of said box-sections, having portions of said ribs cast over the edges of said disks or plates, said ribs and disks or plates capable of being broken away to form an opening or openings in the side or sides of the 75 outlet-box, substantially as set forth.

In testimony that I claim the invention set forth above I have hereunto set my hand this 25th day of October, 1900.

JOHN FOUNTAIN, JR.
